(57) **CLAIM**

The ornamental design for an ice auger cap, as shown and described.

DESCRIPTION

FIG. 1 is a front perspective view of the ice auger cap; FIG. 2 is a rear perspective view of the ice auger cap of FIG. 1;

FIG. 3 is a side and front perspective view of the ice auger cap of FIG. 1;

FIG. 4 is a side and rear perspective view of the ice auger cap of FIG. 1;

FIG. 5 is a front view of the ice auger cap of FIG. 1;

FIG. 6 is a rear view of the ice auger cap of FIG. 1;

FIG. 7 is a side profile view of the ice auger cap of FIG. 1; and,

FIG. 8 is an end profile view of the ice auger cap of FIG. 1. The broken lines shown in the Figures represent portions of the ice auger cap that form no part of the claimed design.
